UNITED STATES PATENT OFFICE.

ROBERT E. NEWCOMB, OF HOLYOKE, MASSACHUSETTS, ASSIGNOR TO WORTHINGTON PUMP AND MACHINERY CORPORATION, OF NEW YORK, N. Y., A CORPORATION OF VIRGINIA.

HYDRAULIC ENGINE.

Application filed October 7, 1921. Serial No. 506,135.

To all whom it may concern:

Be it known that I, ROBERT E. NEWCOMB, a citizen of the United States, residing at Holyoke, county of Hampden, and State of 5 Massachusetts, have invented certain new and useful Improvements in Hydraulic Engines, fully described and represented in the following specification and the accompanying drawings, forming a part of the same.

10 This invention relates to improvements in hydraulic engines.

It is an object of the present invention to provide an improved hydraulic engine especially adapted for deep-well pumps, in 15 which either single or double-acting pistons adapted to operate well-barrel bucket rods, are actuated by water rods receiving their power impulse from a pumping mechanism remotely located with respect to such hydraulic engine. The invention also aims to provide a novel arrangement by which drifting or slipping of the hydraulic engine pistons with respect to the plungers of the 20 remotely situated actuating pump, which 25 may be due to leakage or other causes, will be automatically corrected on starting, and synchronous action of the plungers of the actuating pump and the pistons of the hydraulic engine be automatically maintained, 30 thus assuring full volumetric efficiency of the pumping elements and minimizing the necessity of frequent removal thereof for adjustment, or repair of breakage resulting from displacement.

35 For a full understanding of the invention, a detailed description of preferred constructions for carrying the same into effect will now be given, in connection with the accompanying drawings, and the novel features of the invention then be specifically pointed out in the claims.

In the drawings—

Figure 1 is a diagrammatic showing of a three bucket deep-well pump, with the improved hydraulic engine in its complete form with the means for maintaining synchronous action of the actuating pump and the hydraulic engine;

Figure 2 is a similar view of the actuating pump, looking to the left of Fig. 1;

Figure 3 is a view similar to Fig. 1, showing a modified construction of hydraulic engine, actuating pump and water rod con-

nections for operating such engine, in connection with a two bucket pump;

Figure 4 is an end view looking to the right in Fig. 3, showing the actuating pump cylinders and valved connections to the make-up tank or means for maintaining synchronous action of the hydraulic engine and actuating pump, and

Figure 5 is a top plan view of the actuating pump of Fig. 3, showing the water rod connections thereto.

Referring now to the drawings, and particularly to Fig. 1, the device shown is arranged to operate the bucket rods of a three bucket deep-well pump of the type shown and described in United States Patent No. 1,102,583, dated July 7, 1914. The actuating pump, indicated generally at P and which may be located at the surface of a well or at a point distant from the hydraulic engine W, consists of three single-acting plungers 1, 2, 3, working in vertical cylinders a, b, c and reciprocated through a crank shaft connection of usual construction, the cranks preferably being set at 120° apart. Each of the cylinders a, b, c is connected at its lower or discharge end by water rods or 80 pipes 4, 5, 6 with the lower ends of the well or hydraulic engine cylinders A, B, C, the upper ends of each of the latter cylinders being in communication with each other through a manifold connection D communicating with a make-up tank E, as herein-after described. In the cylinders A, B, C are located pistons 7, 8, 9 having telescoping piston rods 10, 11, 12, having bucket rod extensions 13, 14, 15, respectively, connected 85 to buckets 30, 31, 32.

From the foregoing it will be obvious that as the plungers 1, 2, 3 of the actuating pump P are reciprocated, the pistons 7, 8, 9 of the hydraulic engine will be reciprocated also, 95 the pistons of the hydraulic engine being lifted as the respective plungers in the cylinders of the actuating pump, with which the cylinders of the hydraulic engine are connected, move downward, the liquid behind the pistons 7, 8, 9 passing from one cylinder to the next through the manifold connection D as such pistons move in opposite directions to each other.

Due to leakage or other causes, when the 105 pump is operating or idle, it frequently

happens that one or more of the hydraulic engine pistons may slip or "drift" from correct relationship with respect to the plungers of the actuating pump, and in order to assure synchronous action of the pumping elements, that is, so that the well or hydraulic engine pistons will at all times be free to make full length strokes in each direction by the impulses imparted to them by the actuating pump through the water rod connections thereto, as above described, there is provided a synchronizing means, one preferred embodiment of which will now be described. Each of the cylinders of the actuating pump P is in communication at its discharge end with a tank E, hereinafter referred to as the make-up tank, through an inlet d and outlet e, such inlet and outlet connections being also provided with check and relief valves f, g, respectively. The manifold D, which is intended to permit liquid displaced in one cylinder of the hydraulic engine to enter another cylinder behind the piston therein as such pistons move in opposite position to each other, is also connected by a pipe F to the tank E, such connection being through inlet h and outlet i, the former having a relief valve indicated generally at k located therein, and the latter a check valve l located therein.

The operation of the device so far described is as follows. Assuming now that the hydraulic engine piston A has drifted or slipped to the bottom of its cylinder, and that plunger 1 of the actuating pump is moving upward toward completion of its full stroke, any additional liquid required will be drawn past the check valve g from tank E, while any surplus liquid in the manifold D caused by such displacement of the piston, will be discharged through pipe F past relief valve k in inlet h into the tank E. Thus, on the first complete revolution of the actuating pump, the pistons of the hydraulic engine will be correctly positioned with respect to the plungers of such actuating pump, and efficient action of the pumping elements thereafter assured.

Referring now to the arrangement shown in Fig. 3, the actuating pump, indicated generally at P, is of the opposed piston type, that is, the four cylinders l, m and n, o (Fig. 5) thereof being arranged in alined pairs and having plungers 15, 16 and 17, 18, respectively, working in unison in each alined pair and in opposite direction to the plungers of the opposite alined pair. The cylinders l, m and n, o of the actuating pump are connected by water rods or pipes 19, 20 and 21, 22, respectively, with the cylinders F, G of the hydraulic engine Y, as shown, the latter being located at any desired point in the well, or at a point distant from the actuating pump. The pistons 23, 24 of the hydraulic engine have telescopic

piston rods 25, 26 with bucket rod extensions 27, 28, respectively, which are also telescopically arranged. It will be obvious from the apparatus so far described that as liquid is forced alternately into the opposite ends of the hydraulic engine cylinders by the impulses conveyed to the water rods by the plungers of the actuating pump, the pistons of the well engine will be reciprocated in opposition to the direction of motion of the actuating pump plunger, the cylinder of which is connected to such hydraulic engine cylinder.

In this construction, also, it sometimes happens that the hydraulic engine pistons may drift or slip from correct relationship with respect to the plungers of the actuating pump, due to leakage or other cause while the pump is idle or operating, and in order to assure correct relationship of the pumping elements, that is, so that the hydraulic engine pistons will be automatically adjusted on starting and maintained in proper relation with respect to the plungers of such actuating pump, and be thereby caused to make full length strokes in each direction with consequent full pumping efficiency of the well buckets, there is provided a synchronizing arrangement somewhat similar to that previously described. The present construction, however, dispenses with the manifold and cylinder and make-up tank connections of Fig. 1, each of the cylinders 15, 16 and 17, 18 being in communication with such make-up tank H through inlets s, s and outlet t. The four cylinders are preferably connected to the tank H by T-connections as shown, and the inlets s, s are provided with relief valves of ordinary construction, indicated generally at u, while the outlet t has check valves v, v located in the T-connections, as shown in Fig. 4.

It will be obvious from the foregoing that if piston 24, for instance, in well or hydraulic engine cylinder G, should slip or drift to the bottom of such cylinder while plunger 18 of the actuating pump P is moving outward to complete its stroke, the necessary additional liquid to assure proper positioning of such piston with respect to such actuating pump plunger will be drawn through connection t from make-up tank H, while surplus liquid above such piston will be discharged past the relief valve u in inlet s to tank H, thereby correctly positioning the hydraulic engine piston 24 with respect to the actuating pump plunger 18 on the first revolution of the latter pump.

In the operation of the device, it is probable that very little liquid will be discharged past the relief valves or be drawn past the check valves, as proper adjustment of the hydraulic engine pistons is usually obtained when starting up, and on the first revolution of the actuating pump, and displacement is

due only to leakage or slipping, while the pump is idle or operating, respectively. The relief valves on the make-up tank inlets may be readily adjusted to prevent entrance of liquid under ordinary working conditions, and to open only under a pressure in excess of that required to move the hydraulic engine pistons.

The synchronizing device has been shown only in connection with a plurality of hydraulic engine and actuating pump pistons or plungers, but obviously this synchronizing device is applicable, also, in connection with apparatus having only a single hydraulic engine and actuating pump piston or plunger, and is thus claimed. It will be understood, also, that the invention is not to be confined to use solely with deep-well pumps, but may be readily adapted to apparatus in which hydraulically operated engine pistons are controlled by a distant pump. It is also to be understood that various changes and modifications in the construction and arrangement of parts may be made, while still retaining the invention defined by the claims.

What is claimed is:

1. A hydraulically operated engine, comprising a plurality of cylinders arranged in longitudinal alinement, power transmitting pistons therein, a plurality of telescoping piston rods connected to the respective pistons in said cylinders, water rod connections to said cylinders, means for imparting power impulses to said water rods, and means for synchronizing the movements of said hydraulic engine pistons with respect to each other and said power impulse imparting means.
2. A hydraulically operated engine, comprising a plurality of cylinders arranged in longitudinal alinement, power transmitting pistons therein, a plurality of telescoping piston rods connected to the respective pistons in said cylinders, pumping elements carried by said piston rods, water rod connections to said cylinders, and means for imparting power impulses to said water rods, means for imparting power impulses to said water rods, and means for synchronizing the movements of said hydraulic engine pistons with respect to each other and said power impulse imparting means.
3. A hydraulically operated engine, comprising a plurality of cylinders arranged in longitudinal alinement, power transmitting pistons therein, a plurality of telescoping piston rods connected to the respective pistons in said cylinders, water rod connections to said cylinders, means for imparting power impulses to said water rods at predetermined intervals to cause said hydraulic engine pistons to move in timed relation with respect to each other and said water rod power impulse imparting means.

4. A hydraulically operated engine, comprising a plurality of cylinders, power transmitting pistons therein, water rod connections to said cylinders, an actuating pump for imparting power impulses to said water rods for reciprocating said hydraulic engine pistons, a make-up tank, and inlet and outlet connections thereto from the actuating pump cylinders and the hydraulic engine cylinders for automatically maintaining synchronous movements of said hydraulic engine pistons with respect to each other and the actuating pump plungers. 70 75

5. A hydraulically operated engine, comprising a plurality of cylinders in longitudinal alinement, power transmitting pistons therein, telescoping piston rods connected to said pistons, pumping elements carried by said piston rod extensions, water rod connections to said cylinders, an actuating pump for imparting power impulses to said water rods for reciprocating said pistons, and means for maintaining synchronous action of the hydraulic engine pistons with respect to each other and the actuating pump plungers. 80 85 90

6. A hydraulically operated engine, comprising a plurality of cylinders arranged in longitudinal alinement, power transmitting pistons therein, water rod connections to said cylinders, an actuating pump for imparting power impulses to said water rods for actuating said pistons, a make-up tank, inlet and outlet connections thereto from the actuating pump cylinders and the hydraulic engine cylinders, relief and check valves, respectively, in said inlet and outlet connections, whereby synchronous action of the hydraulic engine pistons with respect to each other and the actuating pump plungers is secured. 95 100 105

7. A hydraulically operated engine, comprising a plurality of cylinders, power transmitting pistons therein, water rod connections to said cylinders, an actuating pump for imparting power impulses to said water rods for actuating said pistons, and a manifold connection between the cylinders of said hydraulic engine to permit displacement of liquid from one cylinder to another as the pistons therein move in opposite directions. 110 115

8. A hydraulically operated engine, comprising a plurality of cylinders, power transmitting pistons therein, water rod connections to said cylinders, an actuating pump for imparting power impulses to said water rods for actuating said pistons, a manifold connection between the cylinders of said hydraulic engine to permit displacement of liquid from cylinder to cylinder as the pistons therein move in opposition to each other, and valved connections between the cylinders of both the actuating pump and the hydraulic engine and the make-up 120 125 130

tank and between the manifold and said tank, for synchronizing the movements of the hydraulic engine pistons with respect to each other and the plungers of the actuating 5 pump, respectively.

9. A hydraulically operated engine, comprising a plurality of cylinders, power transmitting pistons therein, water rod connections to said cylinders, an actuating pump 10 for imparting power impulses to said water rods for actuating said hydraulic engine pistons, a connection between the cylinders of said hydraulic engine to permit displacement of liquid from cylinder to cylinder as 15 the pistons therein move in opposition to each other, and means for automatically synchronizing the movements of the hydrau-

lic engine pistons with respect to each other and the actuating pump plungers.

10. A deep well pump having a plurality 20 of buckets arranged in line, a plurality of cylinders with pistons therein having rods connected to the respective buckets, water rod connections to said cylinders, an actuating pump for imparting power impulses 25 to said pistons through said water rods at predetermined intervals for operating said buckets, and means for synchronizing the movements of the bucket rod pistons with respect to each other and the actuating pump 30 plungers.

In testimony whereof, I have hereunto set my hand.

ROBERT E. NEWCOMB.
